STEPHEN M. CASEY,
Frank Allen

Attorney

UNITED STATES PATENT OFFICE.

STEPHEN M. CASEY, OF SAN FRANCISCO, CALIFORNIA.

DOOR.

Application filed February 16, 1925. Serial No. 9,504.

To all whom it may concern:

Be it known that I, STEPHEN M. CASEY, a citizen of the United States of America, residing at San Francisco, in the county of San Francisco and State of California, have invented certain new and useful Improvements in Doors, of which the following is a specification.

My invention relates to doors in general and particularly to inside doors, specially applicable for use in connection with hospitals, schools or dwellings, which combines the essential requirements of the ordinary door and a screen door and one that can be readily changed at pleasure for a screen or solid door, thereby securing the advantages of both, avoiding the expense and inconvenience of the ordinary screen door, and the resultant difficulties and inconvenience entailed in the placing, removal and storage of the usual screen door. The scope of my invention extends to whatever construction may be defined by or included within the terms or language of the appended claim.

25 In the drawing:

Figure 1 is a front elevation of a door embodying my invention, partly broken away;

Figure 2 is an enlarged longitudinal section of Figure 1, illustrating the glass panel in its raised position;

Figure 3 is a similar view showing the glass panel in its lowered position within the door and

35 Figure 4 is a transverse section on the line 4—4 of Figure 2.

My invention, in the form or embodiment shown in the drawing and briefly described, comprises the stiles, 11, of the door, 10, which may be made double or single, as desired. The rails, 12 and 13, are formed of solid material, whereas, the center rail, 14, is constructed of two boards or strips, 15 and 16. The rails, 13 and 14, and the stiles, 11, are suitably grooved for the purpose of receiving the panels, 15, they being spaced apart, as is clearly illustrated in Figures 2 and 3 of the accompanying drawing.

40 It will be readily seen from Figures 2 and 3, that by forming a door of such a construction, the space or compartment, 17, would extend from the upper edge of the center rail, 14, to the upper edge of the rail, 13.

A groove, 18, is formed in the lower edge

of the upper rail, 12, which aligns with and corresponds to the vertically extending grooves, 19, formed in the inner edges of the stiles, 11. To obtain the best results, 40 I form the grooves, 18 and 19, of approximately the same width as is the space, 17, between the rail sections, 15 and 16.

A window sash, 20, is slidably mounted within the grooves, 19, formed in the stiles, 11, and is snugly fitted when in its raised position, as is shown in Figure 2, within the upper groove or recess, 18, and the upper portion of the space, 17. The pane of glass carried by the sash, 20, may, of course, be 45 supported in any suitable manner. For the purpose of counter-balancing the sash, 20, in its raised or lowered position, I utilize a tape, 21, which is secured at one end to the upper edge of the sash, 20, the opposite 50 end thereof being wound about a spring tension roller located near the upper end of the door, 10, as is clearly shown in Figures 1 and 3.

For readily placing the sash, 20, or removing it for assembly or repair, I provide mouldings or strips, 22, about the opening, 23, formed in the upper end of the door, 10. The opening, 23, may, of course, be varied to suit the particular requirements. 55

A screened sash, 24, is located adjacent to the glassed sash, 20, when in its raised position, as is shown in Figure 2, it being noted that the width of the sash, 24, is substantially the same as the width of the 60 strips, 15, forming a part of the rail, 14, so that the movement of the glassed sash, 20, will not be hindered. For the purpose of retaining the screened sash, 24, in position and to prevent its accidental displacement from within the opening, 23, of the door, 10, I form a rib or bead, 25, integral 65 with the upper edge of the sash frame, 24, which is adapted to fit into a recess, 26, provided in the lower edge of the rail, 12. 70

A door, constructed in accordance with my invention, it will be readily seen, may be readily handled and economically stored or shipped, inasmuch as the screened sash, 24, is flush with the outer surface of the 75 door frame. It will be obvious, with particular reference to Figures 2 and 3, that the screened sash, 24, may be retained in its position without interfering with the movement of the glassed sash, 20, or it may 80 be readily removed from its position within the opening, 23, should it be desired.

I claim:

A door comprising stiles, solid top and bottom rails, a center rail made up of two similar strips with their outer surfaces flush with the similar surfaces of the top and bottom rails and their inner surfaces spaced apart, lower panels between each of the center rail sections and the bottom rail, said lower panels being spaced in continuation of the space between the center rail sections, a window-carrying sash of a thickness to slidably fit in the space between the center rail sections and the lower panels,

said space being filled by the sash when in lowered position, the lower edge of the upper rail being recessed in line with the space between center rails to receive the upper edge of the sash, and a screen-carrying frame arranged and fixedly interfitted between the lower edge of the upper rail at one side of the sash receiving recess and the upper edge of one of the center rails, the inner edge of the screen frame forming a fixed guide for the movement of the sash. 15 20

STEPHEN M. CASEY.
